UNITED STATES PATENT OFFICE.

GEORGE W. NEWMAN, OF CHICAGO, ILLINOIS, ASSIGNOR, BY MESNE ASSIGNMENTS, TO WILSON-JONES LOOSE LEAF COMPANY, OF CHICAGO, ILLINOIS, A CORPORATION OF MASSACHUSETTS.

LOOSE-LEAF BOOK AND METHOD OF ASSEMBLY.

Application filed October 27, 1921. Serial No. 510,870.

To all whom it may concern:

Be it known that I, GEORGE W. NEWMAN, a citizen of the United States, and a resident of the city of Chicago, in the county of 5 Cook and State of Illinois, have invented certain new and useful Improvements in Loose-Leaf Books and Methods of Assembly; and I do hereby declare that the following is a full, clear, and exact description of 10 the same, reference being had to the accompanying drawings, and to the numerals of reference marked thereon, which form a part of this specification.

This invention relates to a loose leaf book 15 and the method of manufacturing the same.

It is an object of this invention to provide a structure that will always retain its shape and improve the appearance of the binder.

It is a further object of this invention to 20 provide a binder having separable parts with novel means for attaching them together.

It is a further object of this invention to 25 provide a novel rear or back structure for the binder that tends to preserve the shape of the binder and hold the parts in proper relation.

It is a further object of this invention to 30 provide a novel manner of assembling the parts of the binder.

With these and other objects in view which will be more apparent in the following description and disclosures, my invention comprises the novel mechanisms and 35 method of assembling hereinafter described and more particularly pointed out and defined in the appended claims.

In the accompanying drawings which illustrate a preferred embodiment of my invention and in which similar reference numerals refer to similar features in the different views:

Figure 1 is a fragmentary transverse sectional view of a binder illustrating certain 45 features of my invention, upon an enlarged scale.

Figure 2 is a fragmentary end elevation thereof upon an enlarged scale.

Figure 3 is a section through the rear anchoring plate, upon an enlarged scale.

Figure 4 is a bottom plan view of the leaf holding means.

Figure 5 is a longitudinal section through the back of the binder illustrating certain

features of securing the leaf holding means, 55 upon an enlarged scale.

Figure 6 is an enlarged fragmentary sectional view of a rear end of the binder.

Figure 7 is a top plan view of the covered back plate shown in section in Figure 3.

Figure 8 is a top plan view of the back plate with the binder cover thereon.

Figure 9 is a top plan view of the assembled leaf holding means with parts of the cover attached.

Figure 10 is a perspective view of the binder in assembled form.

As shown on the drawings:

The book comprising the subject matter of this invention consists preferably of three 70 parts or units, namely, the cover, the leaf retaining device, and the back or rear structure which are provided with novel securing means, whereby they are assembled and interlocked in a novel way.

The cover comprises preferably a piece of 75 pliable leather 1 or composition of leather of such a size as to encompass the sides and bottom of the loose leaves when said leather is folded in its proper book form.

The illustrated leaf retaining device comprises a pair of abutting ring holding members 2 retained in abutting relation by means of a downwardly bowed resilient plate 3 having slight lateral grooves formed by 80 bent over lips at its lateral edges for receiving the outer edges of the ring holding members 2. The lower portion of said spring plate 3 is provided with a slot 4 a short distance to one side of the center 85 thereof and slits 5 adjacent the ends as shown in Figure 4. These slits 5 and slot 4 are preferably arranged upon the center line of the plate. The abutting edges of the plates 2 are supported for conjoint tilting 90 movement. For this purpose cooperating notches are formed in the abutting edges of the plates 2 for loosely receiving the shanks of double-headed rivets or fasteners 6, the heads of which are sufficiently spaced to 95 allow a proper upward or downward tilting movement of said plates. The tilting of these plates is effected by a pair of push buttons 7 or the like, which are anchored between said plates in any suitable manner 100 so as not to interfere with the tilting movements thereof, and these push buttons extend through apertures in the back plate 105

of the rear structure where they are provided with curved heads resting against the sheath of the back plate so as to be operable by pressure against the outer surface of said sheath. At proper intervals, the ring plates 2 are provided with the opposed ring members 8 that hold the loose leaves. The structure of the leaf holding means, however, forms no part of my present invention except in so far as it is provided with means or constructed to cooperate with my invention.

The leaf retaining means or device is preferably provided with a resilient notched cover plate 9 having lateral lips which snap over the spring plate 3, but it should be understood that this cover plate 8 is not applied until the book is completely assembled in other respects, and does not necessarily constitute a part of the leaf holding device as described in this specification.

The rear structure which comprises part of my invention is adapted to be applied to the outside of the cover 1 to form the back 25 of the book consists preferably of an outwardly bowed or curved back plate 10 sheathed by means of a suitable piece of leather 11 or the like; the sheath covering the outer bowed portion and overlapping the lateral edges for a considerable extent 30 inwardly as shown in Figure 3. The sheath may be glued or otherwise secured to the plate 10. The ends of the sheath 11 are provided with flaps 12 having slits 13 as best 35 shown in Figures 7 and 8, and the back plate 10 is provided with upwardly or inwardly directed tongues or lugs 14 adapted for entering said slits when the flaps 12 are superimposed thereon. The plate 10 is further 40 provided with a holding tongue or lug 15 at the center thereof. The tongues 14 and lug 15 of the back plate 10 are adapted to pierce the cover 1 which is provided with suitable slits at the proper center line for 45 this purpose as shown in Figure 8, and be anchored in the slots 5 and 4 of the spring plate 3 respectively. The slots 4 and 5 in the spring plate 3 are broadly termed sockets to receive the tongues 14 and 15 of the back 50 plate 10.

The method of assembling the different parts consists in placing the sheathed plate or rear structure upon its back, placing the cover thereover with the slits thereof engaging the tongues 14 and 15 as best shown in Figure 8 and superimposing the flaps 12 over the cover with the slits 13 engaging the studs 14, then applying the leaf retaining device thereupon by a slight endwise movement to bring the wall of the slot 4 thereof under the lug or tongue 15 as best shown in Figure 5 and the slots 5 in a position to engage over the tongues 14; if necessary, the parts may be slightly flexed for this 65 purpose. The tongues 14 are then crimped

over the upper surface of the spring plate 3 (Figure 5) and the cover 9 applied to the leaf retaining device; then by folding the sides into book form as shown in Figure 10, the binder will be complete and ready for 70 use.

It is characteristic of my invention that the plates 3 and 10 are provided with mutually engaging tongues and sockets, the tongues overlapping the walls of the sockets where- 75 by the parts are securely interlocked together, and that the rear structure or sheathed plate is provided with flaps that overlap the cover and retain the same, in consequence of which the different parts may 80 be said to be interlocked together by overlapping parts.

It should be noted that the cover 1 is securely anchored between the plates 3 and 10, being supported by the plate 3, and that the 85 rear structure provides a rigid support therefor holding the parts in proper relation and insuring long service and a good book- 90 like structure that is not readily liable to break or tear and that safety retains the leaves from being torn therefrom or mutilated by a relative endwise shifting of the covers.

I am aware that numerous details of construction may be varied through a wide 95 range without departing from the principles of this invention, and I therefore do not purpose limiting the patent granted otherwise than necessitated by the prior art.

I claim as my invention:

1. The method of assembling a loose leaf 100 book consisting of superimposing a piece of leather upon a sheathed plate, folding the ends of the sheath over said leather and fastening them to said plate, applying the leaf holding device upon said leather and over said sheathed plate, interlocking the device with said sheathed plate, and applying a cover to said leaf holding device.

2. The method of assembling a loose leaf 110 book consisting of superimposing a cover with its center line upon a sheathed plate, folding the ends of the sheath over the cover, applying the leaf retaining device on said cover and over said sheathed plate, securing said device to said sheathed plate, and folding said cover into book form.

3. The method of assembling a loose leaf 120 book consisting of superimposing a piece of covering upon a sheathed plate, securing the sheathed plate to said covering, applying the leaf retaining device on said covering and over said sheathed plate by an endwise movement, and securing said device to said sheathed plate.

4. In a loose leaf book, a cover, a leaf retaining device in said cover, a rear structure for said cover comprising a member having tongues adjacent its ends, a sheath partially enclosing said member and provided with 125 130

end flaps superimposed on said cover, and anchored to said tongues, said cover and leaf retaining device being provided with slits to receive said tongues for securing the parts together.

5. In a loose leaf book, a cover, a leaf retaining device in said cover, a rear structure for said cover comprising a plate, a sheath partially enclosing said plate and having 10 end flaps, and means for anchoring together

said end flaps, rear structure and leaf retaining device with said end flaps between the cover and leaf retaining device.

In testimony whereof I have hereunto subscribed my name in the presence of two subscribing witnesses.

GEORGE W. NEWMAN.
